UNITED STATES PATENT OFFICE

2,212,280

TOY SUBMARINE

Joseph O. Thorsheim, Minneapolis, Minn.

Application March 18, 1940, Serial No. 324,594

20 Claims.

(Cl. 46—94)

My invention relates to toy submarines and has for an object to provide a toy submarine which will simulate in action an actual submarine.

An object of the invention resides in providing a toy submarine capable of submerging and automatically rising to the surface of the water after a predetermined interval.

A further object of the invention resides in providing a toy submarine which will repeatedly 10 submerge and rise to the surface.

Another object of the invention resides in providing a toy submarine which will submerge and after a predetermined lapse of time will travel ahead in the water and rise therein.

15 Another object of the invention resides in constructing the submarine with a hull having a support for a cake of soluble material, said cake being adapted to cause the submarine to submerge and upon solution in the water causing the 20 submarine to rise to the surface.

A feature of the invention resides in forming in the bottom of the submarine a cavity in which the cake of soluble material is disposed.

A still further object of the invention resides 25 in constructing the submarine so that the water circulates freely about the cake whereby rapid solution of the same may be effected.

An object of the invention resides in providing 30 a cage within said cavity having perforate walls and forming a passageway through which water may circulate, said cage being disposed within said cage.

An object of the invention resides in constructing 35 the cake of layers of different materials or of differently treated materials so that successive portions of the same are dissolved changing the buoyancy of the cake so as to procure alternate submerging and rising of the submarine.

A still further object of the invention resides 40 in utilizing a propeller for propelling the submarine and in employing in conjunction with the propeller a device for controlling movement thereof, said device being actuated upon solution of the cake.

45 A feature of the invention resides in employing a propeller shaft for operating the propeller and in attaching to the propeller shaft an arm adapted to engage the cake and restrain rotation of the shaft.

50 A feature of the invention resides in using the propeller shaft and arm for maintaining the cake within the cavity in the hull.

Another object of the invention resides in venting 55 the cavity in the hull, whereby water will readily enter said cavity.

Other objects of the invention reside in the novel combination and arrangement of parts and in the details of construction hereinafter illustrated and/or described.

In the drawing:

Fig. 1 is a side elevational view of a toy submarine illustrating an embodiment of my invention.

Fig. 2 is a bottom view of the structure shown in Fig. 1.

Fig. 3 is an elevational sectional view taken on line 3—3 of Fig. 1.

Fig. 4 is a view similar to Fig. 3 showing the cake partly dissolved.

Fig. 5 is a view similar to Fig. 4 showing the 15 cake still further dissolved.

Fig. 6 is a perspective view of the cage used for supporting the cake within the cavity in the hull of the submarine.

My invention comprises a hull designated by 20 the reference numeral 10, which may be constructed of wood or other buoyant material or which may be constructed of metal and provided with sufficient air spaces to procure buoyancy of the same. The hull 10 is generally in the form 25 of a submarine having sides 11 and 12 and a bottom 13. The hull 10 may be constructed, as indicated at 16, to simulate the super-structure of a submarine with a periscope 17 and a conning-tower 18.

30 The submarine is provided with a rudder 19. Ahead of the rudder and attached to the bottom 13 of the hull 10 is a bracket 21 which forms a bearing for a propeller shaft 22. This shaft 22 follows along the underside of the bottom 13 35 and is positioned in close proximity thereto. The rearward end of the shaft 22 has attached to it a propeller 23 which has a hub 24 bearing against the bracket 21. The other end 29 of the shaft 22 is constructed with a hook 25 over which one 40 end of a rubber band 26 is hooked. The other end of the said band is hooked on a fixed hook 27 which is screwed into the bottom 13 of the hull 10. It will readily be comprehended that, when the propeller shaft 22 is rotated the band 26 45 is twisted and energy stored up in the same, which, when the shaft 22 is released causes the propeller 23 to rotate and drive the submarine forward in the water.

In the bottom 13 of the hull, intermediate the 50 ends thereof and midway between its sides 11 and 12, is formed a rectangular cavity 28. This cavity has side walls 31 and 32 and a top 33, said cavity being open at the bottom so that water may readily enter the same. A vent 36 for the 55

cavity 28 is provided in the hull 10 to prevent the trapping of air in said cavity and thus permit water readily to enter the cavity for a purpose presently to be described.

Within the cavity 28 is disposed a cage 37 formed with a top 38 and side and end walls 39 and 41, the bottom of said cage being open. This cage is constructed of suitable sheet material and the various walls thereof are perforate, being formed with numerous large openings 42 therein through which water may readily enter the cage from the top, sides and ends thereof, as well as from the bottom. The walls 39 have ears 43 projecting outwardly therefrom. The dimensions of the cage 37 are somewhat less than those of the cavity 28 so that the walls 39 and 41 become spaced from the walls 31 and 32 of the cavity 28 and so that the top 38 of the cage becomes spaced from the top 33 of cavity 28. In this manner a passageway 44 is formed between the walls of the cage 37 and the walls of the cavity 28, whereby water may enter the cavity and circulate freely about and through the cage 37. Said cage 37 is supported through the two ears 43 which are attached to the bottom 13 of the hull 10 by means of nails or screws 45, best shown in Fig. 2.

Within the interior of the cage 37 is disposed a cake 46 which is constructed of materials readily soluble in water. This cake consists of a core 49, an intermediate portion 48 enrobing the core, and a jacket 47 enrobing said intermediate portion 48. Each of these various portions consists of water-soluble material. The core 49 and jacket 47 may be of the same material and will have a specific gravity, greater than that of water, while the material from which the intermediate portion 48 is formed will have a specific gravity less than that of water. The thickness of the various portions of the cake 46 and the relative weights thereof are so proportioned that the ratio of the weight of the entire cake to its volume is greater than that of water. Also the weight of the entire cake is sufficient so that the cake, when inserted into the cage 37, and the submarine placed in the water, overbalances the buoyancy of the submarine and causes the same to submerge. The ratio of the weight of the intermediate portion 48 and its enrobed core 49 to the volume of the former is preferably less than that of water so that, after the jacket 47 has been dissolved, the cake becomes buoyant and causes the submarine to rise. It can readily be comprehended that the ratio of the weight to volume of the intermediate portion 48 and its enrobed core 49 can be made equal to that of water or even slightly greater than water if the combined weight of both portions 48 and 49 be kept below the buoyancy of the hull. However, best results are produced when the ratio is less than that of water so that the buoyancy of the cake, devoid of the jacket 47, tends to cause the submarine to rise. The ratio of the weight of the core 49 to its volume is greater than that of water and said core is of such weight that, when denuded of the intermediate portion 48, it will cause the submarine to submerge.

In forming the cakes 46, various chemicals and materials which are soluble in water may be used. Ordinary table salt or sugar may be utilized. Buoyancy of the cake may be procured by trapping air with the particles of soluble substance, such air being released as the substance dissolves. Or if desired, substances or materials of low

specific gravity may be used to provide buoyancy in the cake.

As will be noted in Figs. 1 and 2, the forward portion 29 of shaft 22 extends across the open underside of the cavity 28. At this locality a cross arm 51 is provided which is welded or otherwise secured to the said shaft. This cross arm engages the cake 46 and prevents rotation of the shaft 22. When the jacket 47 and intermediate portion 48 and a substantial portion of the core 10 49 of said cake are dissolved, arm 51 is released and the propeller shaft 22 permitted to rotate. This shaft 22 is loosely journaled in the bearing formed in bracket 21 so that the portion 29 of said shaft may be swung clear of the bottom 13 15 of the hull in proximity to the cavity 28. This permits the insertion of the cake 46 into the cage 37. When the shaft 22 is released, the elastic band 26 returns said shaft to its normal position, bringing the cross arm 51 into engagement with the underside of the cake 46 and thus holding said cake in position within the cage 37.

The operation of the illustrated embodiment of my invention is as follows: The shaft 22 is first turned by hand in a direction opposite to that through which the propeller 23 turns in propelling the boat. This twists the elastic band 26, storing up energy in the same. After the said band has been sufficiently twisted, the shaft 22 is swung clear of the cavity 28 in the hull 10. The cake 30 46 is then inserted into the cage 37 and the cross arm 51 brought flatly into engagement with the underside of the cake, as shown in Fig. 3. The tension on the band 26 holds the structure, as shown in Fig. 1, with the cake 46 retained in 35 position through the cross arm 51. When the submarine is placed in the water, it is caused by the weight of the cake 46 to sink and become completely submerged. Water, of course, enters the cavity 28 and the air within said cavity 40 escapes through the vent 36. It will readily be comprehended that the water may circulate through the space 32 in the cavity 28 and freely enter the cage 37 through the openings 42 in the various walls thereof. The water entering the 45 cage through said openings and through the open bottom thereof first dissolves the jacket 47 of the cake 46. This reduces the weight of the said cake and upon substantially complete solution of said jacket the submarine rises to the surface of 50 the water. As the jacket 47 is dissolved, the cross arm 51 follows the gradually changing surface of the cake. When the jacket has been completely dissolved the position of the cross arm, with reference to the cake, is as shown in Fig. 4. Upon 55 reaching the surface of the water, the submarine floats, the remainder of the cake 46 being still submerged. During flotation of the submarine the intermediate portion 48 of the cake commences to dissolve and as it dissolves, the ratio 60 of the weight to volume of the remainder of the cake increases until a point is reached at which the ratio is greater than that of water. When this ratio becomes sufficiently great, which is accomplished when substantially all of the intermediate portion 48 has been dissolved, the weight 65 of the core 49 causes the submarine again to submerge. The position of the cross arm 51, with reference to the core 49, when the intermediate portion 48 and jacket 49 of the cake have both 70 been dissolved is shown in Fig. 5. Solution of the core 49 then progresses until the cross arm 51 is released thereby. When this occurs, the undissolved fragment of said core drops from the cage 37, whereupon the submarine begins to rise 75

and the propeller shaft 22 begins to turn and drive the rising submarine forward. Thus, it is apparent that the submarine is caused repeatedly to submerge and rise and to be propelled upon its 5 final ascent.

The layers of the cake need not completely en-robe each other, as shown, but may be simply stratified layers which are successively exposed to the water to effect the repeated submerging 10 and emerging of the toy. And, too, the cake may have a uniform foundation throughout and be without layers of different materials or differently treated material, where it is desired only to provide for a single submergence of the toy followed 15 by the emersion thereof.

The device is adapted also to simulate a power driven boat and in such use, a delayed action of the propeller may be had, without submergence of the toy, by using a water-soluble cake of such 20 material that the ratio of the weight of the cake to its volume, as compared with that of water, is insufficient to overcome the buoyancy of the toy. In such case, the toy will merely float until the cake has become sufficiently disintegrated by so- 25 lution to release the cross bar 51, whereupon the propeller shaft will be turned by the twisted band 26 and the toy driven forward by the propeller 23.

The advantages of my invention are manifest. An extremely simple construction is provided.

30 By means of the cakes used, the device becomes wholly automatic. The cakes can be constructed of various harmless materials treated in different ways. There are very few parts to get out of order. The submarine operates in an extremely 35 interesting and attractive manner simulating the maneuvers of actual submarines. The cake used with the invention serves a two-fold purpose, first to cause the submarine to submerge and rise and secondly to control the action of the propeller or any other movable part of the 40 submarine. The use of the invention is extremely simple and a child can easily learn to manipulate and operate the same. The cakes can be constructed at little expense and are easily replaced.

45 Changes in the specific form of my invention, as herein disclosed, may be made within the scope of what is claimed without departing from the spirit of my invention.

Having described my invention, what I claim as 50 new and desire to protect by Letters Patent is:

1. A toy submarine comprising a hull of sufficient buoyancy to float and having a cavity thereinto in which water may enter from the body thereof in which the submarine is disposed, a cake 55 in said cavity formed of a material readily soluble in water, said material having a specific gravity greater than that of water, and said cake being of sufficient size to overcome the buoyancy of the hull and cause the submerging of the submarine, said cake upon solution becoming dispersed in 60 said body of water and rendering the submarine free to rise in the water.

2. A toy submarine comprising a hull of sufficient buoyancy to float, a water-soluble substance 65 adapted to be carried by the submarine and exposed to the water in which it is placed, said substance being of sufficient bulk and specific gravity to cause the submarine to submerge, said submarine being adapted to rise in the water upon 70 the solution of said substance therein.

3. A toy submarine comprising a hull of sufficient buoyancy to float, a support on said hull, a cake soluble in water and carried by said support, the ratio of the weight of said cake to its volume 75 being greater than that of water, said cake being

of sufficient weight to cause submergence of the submarine, said support being arranged to expose the cake to the water in which the submarine is placed to cause the solution of the cake in the water, said submarine being adapted to rise to 5 the surface of the water upon solution of the cake therein.

4. A toy submarine comprising a hull of sufficient buoyancy to float, a support on said hull, a cake consisting of two portions both soluble in 10 water, the ratio of the weight of said cake to the volume thereof being greater than that of the water and the weight of said cake being sufficient to cause submerging of the submarine, said cake being carried on said support and exposed to the 15 water in which the submarine is placed, one portion of said cake being first exposed and the other portion subsequently exposed after the solution of said first portion, the ratio of the weight to the volume of said second portion being sufficiently 20 near that of water to permit the ascent of the submarine upon solution of said first portion, a movable member carried by the submarine, and means engaging said cake for controlling movement of said member, said means becoming actuated upon solution of one of said portions of 25 said cake.

5. A toy submarine comprising a hull, a cake formed with two portions both thereof being soluble in water, a support on said hull carrying said cake and exposing it to the water in which the submarine is placed, first exposing one portion and, after it is dissolved, then exposing the second portion, the ratio of the weight to volume 30 of the two portions being greater than the ratio of the weight to volume of said second portion, said submarine being adapted to sink in the water with both portions of said cake on said support and adapted to rise with only the second portion 35 of said cake remaining after solution of said first portion.

6. A toy submarine comprising a hull of sufficient buoyancy to float, a cake formed of three portions, all thereof being soluble in water, a support on the hull carrying said cake and exposing it to the water in which the submarine is placed so that one portion is exposed and dissolved and then the second and then the third, the ratio of the weight of the entire cake to its 45 volume being greater than that of water and the weight of said cake being sufficient to cause submerging of the submarine, the ratio of the weight of said second and third portions of the cake to the volume thereof being less than that of water and the volume thereof being sufficient to cause the submarine to rise upon solution of said first portion, the ratio of the weight of the third portion to the volume thereof being greater than that of water and the weight thereof being sufficient to cause the submarine to submerge upon 50 solution of said second portion of the cake, solution of said third portion of said cake freeing the submarine and permitting it to rise again to the 55 surface of the water.

7. A toy submarine adapted to submerge and emerge repeatedly, the same comprising a hull of sufficient buoyancy to float in water, a water-soluble cake consisting of a core, an intermediate portion enrobing the core, and a jacket enrobing 60 said intermediate portion, a support on said hull for said cake, said support being arranged to procure contact of substantially the entire surface area of the cake with the water in which the submarine is disposed, whereby said jacket, in- 65 70 75

termidate portion and core of said cake are caused to dissolve successively in the water, said entire cake being of such relative weight and volume as to cause the submarine to sink, the 5 intermediate portion and core of said cake remaining in the course of its solution being of such relative weight and volume as to cause the submerged submarine to rise, the core of said cake remaining in the further course of its solution being of such relative weight and volume as to cause the submarine again to sink, the solution of a substantial portion of said core, permitting the submarine again to rise.

8. A toy submarine comprising a hull having sufficient buoyancy to float, a receiver on the hull, a water-soluble cake disposed within said receiver and exposed to the water in which the submarine is placed, the ratio of the weight of said cake to the volume thereof being greater than that of water and the weight of said cake being sufficient to cause submerging of the submarine, said cake upon solution becoming dispersed in the water, thus freeing the submarine and permitting it to rise to the surface of the water.

9. A toy submarine comprising a hull having sufficient buoyancy to float, a receiver on the hull, a water-soluble cake disposed within said receiver and exposed to the water in which the submarine is placed, the ratio of the weight of said cake to the volume thereof being greater than that of water and the weight of said cake being sufficient to cause the submarine to submerge, said cake, upon solution, being disintegrated in the water, thus freeing the submarine and permitting it to rise to the surface, means for propelling the submarine, control means engaging the cake and thereby rendering the propeller means inoperative, said control means being released from said cake upon its disintegration and serving thereupon to render said propelling means operative, said control means serving also to retain said cake in said receiver.

10. A toy submarine comprising a hull having sufficient buoyancy to float, a receiver on the hull, a water-soluble cake disposed within said receiver and exposed to the water in which the submarine is placed, the ratio of the weight of said cake to the volume thereof being greater than that of water and the weight of said cake being sufficient to cause the submarine to submerge, said cake, upon solution, being disintegrated in the water, thus freeing the submarine and permitting it to rise to the surface, means for propelling the submarine, control means engaging the cake and thereby rendering the propeller means inoperative, said control means being released from said cake upon its disintegration and serving thereupon to render said propelling means operative.

11. A toy submarine comprising a hull having sufficient buoyancy to float, a receiver on the hull, a water-soluble cake disposed within said receiver and exposed to the water in which the submarine is placed, the ratio of the weight of said cake to the volume thereof being greater than that of water and the weight of said cake being sufficient to cause the submarine to submerge, said cake, upon solution, being disintegrated in the water, thus freeing the submarine and permitting it to rise to the surface, and means for propelling the submarine, said means serving also to retain said cake in said receiver.

12. A toy submarine comprising a hull having a cavity therein and of sufficient buoyancy to float, the water in which the submarine is dis-

posed being adapted to freely enter said cavity, a perforate cage within said cavity spaced from the walls thereof, said cage being arranged to permit of circulation of water from the exterior of the submarine and about said cage and through the perforations thereof into the cage from all sides of the cage, a soluble cake in said cage, the ratio of the weight of said cake to the volume thereof being greater than that of water and the weight of said cake being sufficient to cause submerging of the submarine, said cake upon solution dissolving in the water circulating through said cage and cavity and upon solution causing the submarine to rise to the surface of the water.

13. A toy submarine comprising a hull of sufficient buoyancy to float, a support on said hull, a water-soluble cake carried by said hull and exposed to the water in which the submarine is placed, the ratio of the weight of said cake to the volume thereof being greater than that of water and the weight of said cake being sufficient to cause the submarine to submerge, a movable member carried by the submarine, and means for controlling movement of said member engaging said cake, said means becoming actuated upon solution of said cake.

14. A boat-like toy comprising a hull, a movable element carried thereby, means for controlling the movement of said element, said control means including a water-soluble cake carried by said hull and exposed to the water in which the toy is placed, also a member engaging said cake, said member becoming free from the cake upon solution of said cake and rendering said movable element operative.

15. A toy having means for propelling the same, said means including a movable element, and means for controlling the movement of said element, said control means including a soluble cake exposed for contact with a solvent, also a member engaging said cake, said member becoming freed from said cake upon its solution and rendering said movable element operative.

16. A toy submarine comprising a hull of sufficient buoyancy to float, a support on said hull, a cake readily soluble in water and carried by said support, the ratio of the weight of said cake to the volume thereof being greater than that of water and the weight of said cake being sufficient to cause the submarine to submerge, a propeller for propelling the submarine, a shaft supporting said propeller, a resilient member connected to said shaft and yieldingly applying a rotative force thereto, and an arm carried by said shaft and adapted to engage said cake, said cake restraining rotation of said shaft through engagement with said arm, said arm being freed upon solution of the cake and rendering said shaft operative to propel the submarine.

17. A toy submarine comprising a hull having a cavity in the bottom thereof exposed from beneath the submarine, said hull being of sufficient buoyancy to float, means at the rearward portion of the submarine forming a bearing, a shaft journaled in said bearing and extending along the bottom of the submarine and at a locality in proximity to said cavity, an arm carried by said shaft and rotatable with said shaft within said cavity, a resilient member attached at one end to said shaft, means securing the other end of the resilient member to the hull at the forward portion of the submarine, a soluble cake disposed within said cavity, said arm engaging said cake and restraining rotation of the

shaft thereby, said cake upon being dissolved freeing said arm to procure rotation of said shaft and propulsion of the submarine.

18. A toy submarine comprising a hull having a cavity in the bottom thereof exposed from beneath the submarine, said hull being of sufficient buoyancy to float, means at the rearward portion of the submarine forming a bearing, a shaft journaled in said bearing and extending along the bottom of the submarine and at a locality in proximity to said cavity, an arm carried by said shaft and rotatable with said shaft within said cavity, a resilient member attached at one end to said shaft, means securing the other end of the resilient member to the hull at the forward portion of the submarine, said resilient member yieldingly applying a rotative force to said shaft, a portion of said shaft and said arm overlying the exposed portion of said cavity, said shaft being movable in said bearing and said resilient member yielding to permit of movement of said arm and the overlying portion of said shaft away from said cavity to give access thereto, and a soluble cake disposed within said cavity and held in position therein through said arm, said cake restraining rotation of said shaft

through engagement with said arm, said cake upon solution freeing the arm and rendering said shaft operable to propel the submarine.

19. In combination, a normally inoperative movable element, control means for controlling movement thereof, said control means including a soluble cake and a movable member engaging the cake and restrained from movement thereby, said cake having a portion thereof disposed for contact with a solvent, said engaging member, upon solution of the cake, becoming freed therefrom rendering said movable element operative. 5

20. A toy submarine comprising a hull having a downwardly opening vented cavity in the bottom thereof, said hull being of sufficient buoyancy 15 to float, the water in which the submarine is placed being adapted freely to enter said vented cavity from the underside of the hull, a readily soluble cake held in said cavity, the ratio of the weight of said cake to the volume thereof being greater than that of water and the weight of 20 said cake being sufficient to cause submerging of the submarine, said cake upon solution becoming dispersed in the water and freeing the submarine of the weight of said cake. 25

JOSEPH O. THORSHEIM.
